(57) **ABSTRACT**

A hard surface cleaning concentrate packet, is provided including: water soluble film; concentrated hard surface cleaning composition, comprising: glycol ether of formula I

wherein R¹ is a linear or branched C₂₋₈ alkyl group; wherein each R² is independently selected from hydrogen and methyl; and wherein a is 1 to 3; a nonionic surfactant of formula II

wherein w is 5 to 40; wherein R³ is a hydrogen and a linear or branched C₁₋₂₀ alkyl group; wherein R⁴ is selected from a linear or branched C₁₋₂₀ alkyl group and a linear or branched C₁₋₄ hydroxylalkyl group; wherein each R⁵ is independently hydrogen, methyl, ethyl, n-propyl, iso-propyl, n-butyl, 2-butyl and 2-methyl-2-butyl; and with the proviso that sum of the total number of carbon atoms in R³ and R⁴ is 5 to 21; and a tertiary amine; wherein the water soluble film encapsulates the concentrated hard surface cleaning composition.

HARD SURFACE CLEANING
CONCENTRATE PACKET

The present invention relates to a hard surface cleaning concentrate packet and a method of making and using the same. In particular, the present invention relates to a hard surface cleaning concentrate packet, comprising: a water soluble film; a concentrated hard surface cleaning composition, comprising: a glycol ether of formula I

wherein R^1 is a linear or branched C_{2-8} alkyl group, wherein each R^2 is independently selected from the group consisting of a hydrogen and a methyl group, and wherein a is 1 to 3; a nonionic surfactant of formula II

wherein w is an average of 5 to 40; wherein R^3 is selected from the group consisting of a hydrogen and a linear or branched C_{1-20} alkyl group; wherein R^4 is selected from the group consisting of a linear or branched C_{1-20} alkyl group and a linear or branched C_{1-4} hydroxyalkyl group; wherein each R^5 is independently selected from the group consisting of a hydrogen, a methyl group, an ethyl group, a n-propyl group, an iso-propyl group, a n-butyl group, a 2-butyl group and a 2-methyl-2-butyl group; and with the proviso that sum of the total number of carbon atoms in R^3 and R^4 is 5 to 21; and a tertiary amine; wherein the water soluble film encapsulates the concentrated hard surface cleaning composition.

Cleaning hard surfaces is often accomplished through the use of a surface cleaner that is applied directly onto the surface, and then wiped off with a cloth, squeegee, or other means. Surface cleaners often include various combinations of anionic surfactants, nonionic surfactants, amphoteric surfactants, solvents and chelating agents. Other ingredients often include ammonia, acetic acid, and water.

Because the surface cleaners are generally effective in solution with water, it is possible to provide a concentrate that can be mixed with water to form the cleaning solution. The concentrate may be packaged and shipped separately from the majority of the water used to make the cleaning solution. The end user may then form the cleaning solution from water and the concentrate. A problem with the concentrates is that they benefit from precise mixing to ensure proper concentration of actives in the surface cleaner formed. Too dilute of a solution may result in poor cleaning performance. Too concentrated a solution may result in residue remaining on the cleaned surface. In addition, too concentrated of a cleaning solution may constitute a waste of the cleaning concentrate.

To alleviate concerns with improper dilution of the cleaning concentrate, it has been found beneficial to package single use, pre-measured amounts of cleaning concentrate in individual packages. A premeasured amount of cleaning concentrate is preferably added to a specific volume of water to form a properly concentrated cleaning solution. It is further possible to package the concentrate with a properly sized container such that the user simply adds the cleaning concentrate to the container and fills the remainder of the container with water. When the container is empty, a

replacement package of concentrate may be added to the container, and the remainder once again filled with water.

It has also been found useful to package cleaning concentrates in water soluble packaging, particularly in single use, premeasured amounts. Forming the cleaning solution is made easier by the use of water soluble packaging containing the concentrate because the user may simply add the water soluble package to a container and then add the correct amount of water to form the desired cleaning solution. As the water soluble packaging dissolves, the cleaner is released and forms a cleaning solution having the proper concentration of cleaner.

One problem with conventionally packaged hard surface cleaning concentrates in water soluble packaging is that hard surface cleaning use formulations formed therewith are not particularly effective for cleaning oily and greasy soils from hard surfaces.

Accordingly, there remains a continuing need for hard surface cleaning concentrate packets for use in prepared hard surface cleaning use compositions that are effective for removing oily and greasy soils from hard surfaces.

The present invention provides a hard surface cleaning concentrate packet, comprising: a water soluble film; a concentrated hard surface cleaning composition, comprising: a glycol ether of formula I

wherein R^1 is a linear or branched C_{2-8} alkyl group, wherein each R^2 is independently selected from the group consisting of a hydrogen and a methyl group, and wherein a is 1 to 3; a nonionic surfactant of formula II

wherein w is an average of 5 to 40; wherein R^3 is selected from the group consisting of a hydrogen and a linear or branched C_{1-20} alkyl group; wherein R^4 is selected from the group consisting of a linear or branched C_{1-20} alkyl group and a linear or branched C_{1-4} hydroxyalkyl group; wherein each R^5 is independently selected from the group consisting of a hydrogen, a methyl group, an ethyl group, a n-propyl group, an iso-propyl group, a n-butyl group, a 2-butyl group and a 2-methyl-2-butyl group; and with the proviso that sum of the total number of carbon atoms in R^3 and R^4 is 5 to 21; and a tertiary amine; wherein the water soluble film encapsulates the concentrated hard surface cleaning composition.

The present invention provides a hard surface cleaning concentrate packet, comprising: a water soluble film; a concentrated hard surface cleaning composition, comprising: a glycol ether of formula Ia

wherein R^1 is a linear or branched C_{2-8} alkyl group, wherein b is an average of 0 to 3, wherein c is an average of 0 to 3, and with the proviso that $b+c$ is an average of 1 to 3; a nonionic surfactant of formula IIa

wherein x is an average of 8 to 10; wherein y is an average of 0 to 6; wherein R³ is selected from the group consisting of a hydrogen and a linear or branched C₁₋₁₅ alkyl group; wherein R⁴ is selected from the group consisting of a linear or branched C₁₋₁₅ alkyl group and a linear or branched C₁₋₃ hydroxyalkyl group; and with the proviso that the sum of the total number of carbon atoms in R³ and R⁴ is 6 to 20; and a tertiary amine; wherein the water soluble film encapsulates the concentrated hard surface cleaning composition.

The present invention provides a method of making a hard surface cleaning concentrate packet, comprising: providing a water soluble film; selecting a glycol ether of formula I

wherein R¹ is a linear or branched C₂₋₈ alkyl group, wherein each R² is independently selected from the group consisting of a hydrogen and a methyl group, and wherein a is 1 to 3; selecting a nonionic surfactant of formula II

wherein w is an average of 5 to 40; wherein R³ is selected from the group consisting of a hydrogen and a linear or branched C₁₋₂₀ alkyl group; wherein R⁴ is selected from the group consisting of a linear or branched C₁₋₂₀ alkyl group and a linear or branched C₁₋₄ hydroxyalkyl group; wherein each R⁵ is independently selected from the group consisting of a hydrogen, a methyl group, an ethyl group, a n-propyl group, an iso-propyl group, a n-butyl group, a 2-butyl group and a 2-methyl-2-butyl group; and with the proviso that sum of the total number of carbon atoms in R³ and R⁴ is 5 to 21; selecting a tertiary amine; providing the selected glycol ether of formula I; providing the selected nonionic surfactant of formula II; providing the selected tertiary amine; combining the selected glycol ether of formula I, the selected nonionic surfactant of formula II and the selected tertiary amine to form a concentrated hard surface cleaning composition; forming the hard surface cleaning concentrate packet by disposing the concentrated hard surface cleaning composition within an enclosed volume formed by water soluble film, wherein the water soluble film encapsulates the concentrated hard surface cleaning composition.

The present invention provides a method for removing oily, greasy, tough & stubborn soils from a hard surface, comprising: providing a soiled hard surface; providing a container; providing a dilution water; selecting a hard surface cleaning concentrate packet prepared according to the method of the present invention; providing the selected hard surface cleaning concentrate packet; combining the selected hard surface cleaning concentrate packet and the dilution water in the container to form a hard surface cleaning use composition; wetting the soiled hard surface with the hard surface cleaning use composition; and wiping the wetted soiled hard surface to provide a cleaned hard surface.

DETAILED DESCRIPTION

The hard surface cleaning concentrate packet of the present invention provides a concentrated hard surface cleaning composition with enhanced performance removing oily and greasy soil from hard surfaces (preferably, wherein the concentrated hard surface cleaning composition is easily diluted in room temperature water without the need to apply heat; preferably, wherein the concentrated hard surface cleaning composition does not exhibit undesirable ammonia odor upon dilution).

Unless otherwise indicated, ratios, percentages, parts, and the like are by weight. Weight percentages (or wt %) in the composition are percentages of dry weight, i.e., excluding any water that may be present in the composition. Percentages of monomer units in the polymer are percentages of solids weight, i.e., excluding any water present in a polymer emulsion.

Preferably, the hard surface cleaning concentrate packet of the present invention, comprises: a water soluble film (preferably, wherein the water soluble film has a disintegration time of less than 90 seconds as determined at 40° C. using distilled water according to MSTM 205 when measured independently from the concentrated hard surface cleaning composition); a concentrated hard surface cleaning composition, comprising: a glycol ether of formula I (preferably, 15 to 50 wt % (more preferably, 20 to 40 wt %; still more preferably, 25 to 30 wt %; most preferably, 26 to 28 wt %), based on weight of the concentrated hard surface cleaning composition, of the glycol ether of formula I)

wherein R¹ is a linear or branched C₂₋₈ alkyl group; wherein each R² is independently selected from the group consisting of a hydrogen and a methyl group; and wherein a is 1 to 3; a nonionic surfactant of formula II (preferably, 20 to 60 wt % (more preferably, 25 to 50 wt %; still more preferably, 30 to 40 wt %; most preferably, 34 to 38 wt %), based on weight of the concentrated hard surface cleaning composition, of the nonionic surfactant of formula II)

wherein w is an average of 5 to 40 (preferably, 7 to 27; more preferably, 8 to 20; most preferably, 7 to 12); wherein R³ is selected from the group consisting of a hydrogen and a linear or branched C₁₋₂₀ alkyl group; wherein R⁴ is selected from the group consisting of a linear or branched C₁₋₂₀ alkyl group and a linear or branched C₁₋₄ hydroxyalkyl group; and wherein each R⁵ is independently selected from the group consisting of a hydrogen, a methyl group, an ethyl group, a n-propyl group, an iso-propyl group, a n-butyl group, a 2-butyl group and a 2-methyl-2-butyl group (preferably, a hydrogen, a methyl group and an ethyl group; more preferably, a hydrogen and a methyl group; most preferably, a hydrogen); with the proviso that sum of the total number of carbon atoms in R³ and R⁴ is 5 to 21; and a tertiary amine (preferably, 15 to 60 wt % (more preferably, 20 to 50 wt %; still more preferably, 25 to 40 wt %; most preferably, 27 to 34 wt %), based on weight of the concentrated hard surface cleaning composition, of the tertiary amine)(preferably, wherein the tertiary amine is of formula III)

wherein R⁶, R⁷ and R⁸ are independently selected from a linear or branched C₁₋₂₀ alkyl group and a linear or branched C₁₋₂₀ hydroxyalkyl group (preferably; a linear or branched C₁₋₁₀ alkyl group and a linear or branched C₁₋₁₀ hydroxyalkyl group; more preferably, a branched C₃₋₅ alkyl group or a branched C₃₋₅ hydroxyalkyl group; most preferably, a branched C₃ hydroxyalkyl group); wherein the water soluble film encapsulates the concentrated hard surface cleaning composition.

Preferably, the hard surface cleaning concentrate packet of the present invention, comprises: a water soluble film, wherein the water soluble film has a disintegration time of less than 90 seconds as determined at 40° C. using distilled water according to MSTM 205 when measured independently from the concentrated hard surface cleaning composition. More preferably, the hard surface cleaning concentrate packet of the present invention, comprises: a water soluble film, wherein the water soluble film has a disintegration time of less than 90 (preferably, less than 60; more preferably, less than 40; most preferably, less than 30) seconds as determined at 40° C. (preferably, at 30° C.; more preferably, at 25° C.; most preferably, at 21° C.) using distilled water according to MSTM 205 when measured independently from the concentrated hard surface cleaning composition. Most preferably, the hard surface cleaning concentrate packet of the present invention, comprises: a water soluble film, wherein the water soluble film has a disintegration time of less than 90 (preferably, less than 60; more preferably, less than 40; most preferably, less than 30) seconds as determined at 40° C. (preferably, at 30° C.; more preferably, at 25° C.; most preferably, at 21° C.) using distilled water according to MSTM 205 when measured independently from the concentrated hard surface cleaning composition; and wherein the water soluble film comprises (consists essential of, or consists of) a material selected from the group consisting of polyvinyl alcohol, polyvinyl acetate, hydrolyzed polyvinyl acetate (preferably, polyvinyl acetate that is 88 to 98% hydrolyzed), gelatin and combinations thereof. Preferably, the water soluble film includes polyvinyl alcohol. Such water soluble films include, for example, those commercially available from Monosol under trade names A127, A200, L330, L336, L336 Blue, L711, L711 Blue, M1030, M1030, M2000, M2631A, M3030, M6030, M7030, M7031, M7061, M8310, M8440, M8534, M8630, M8900 and M9500.

Preferably, the hard surface cleaning concentrate packet of the present invention, comprises: a single layer or multiple layers of the water soluble film. Preferably, each water soluble film layer has a thickness of 5 to 200 (preferably, 5 to 100; more preferably, 20 to 85; still more preferably, 30 to 70; most preferably, 40 to 60) microns.

Preferably, the hard surface cleaning concentrate packet of the present invention, comprises: a concentrated hard surface cleaning composition, comprising: 15 to 50 wt % (preferably, 20 to 40 wt %; more preferably, 25 to 30 wt %; most preferably, 26 to 28 wt %), based on weight of the concentrated hard surface cleaning composition, of a glycol ether of formula I

(I)

wherein R¹ is a linear or branched C₂₋₈ alkyl group (preferably, a linear or branched C₃₋₈ alkyl group; more preferably, a linear C₄₋₇ alkyl group; most preferably, a linear C₆ alkyl group); wherein each R² is independently selected from the group consisting of a hydrogen and a methyl group (preferably, wherein each R² is a hydrogen); and wherein a is 1 to 3 (preferably, wherein a is 2). More preferably, the hard surface cleaning concentrate packet of the present invention, comprises: a concentrated hard surface cleaning composition, comprising: 15 to 50 wt % (preferably, 20 to 40 wt %; more preferably, 25 to 30 wt %; most preferably, 26 to 28 wt %), based on weight of the concentrated hard surface cleaning composition, of a glycol ether of formula I; wherein R¹ is a linear C₄₋₇ alkyl group and wherein a is 2. Most preferably, the hard surface cleaning concentrate packet of the present invention, comprises: a concentrated hard surface cleaning composition, comprising: 15 to 50 wt % (preferably, 20 to 40 wt %; more preferably, 25 to 30 wt %; most preferably, 26 to 28 wt %), based on weight of the concentrated hard surface cleaning composition, of a glycol ether of formula I; wherein R¹ is a linear C₆ alkyl group and wherein a is 2.

Preferably, the hard surface cleaning concentrate packet of the present invention, comprises: a concentrated hard surface cleaning composition, comprising: 15 to 50 wt % (preferably, 20 to 40 wt %; more preferably, 25 to 30 wt %; most preferably, 26 to 28 wt %), based on weight of the concentrated hard surface cleaning composition, of a glycol ether of formula Ia, wherein the glycol ether of formula I is of formula Ia

(Ia)

wherein R¹ is a linear or branched C₂₋₈ alkyl group (preferably, a linear or branched C₃₋₈ alkyl group; more preferably, a linear C₄₋₇ alkyl group; most preferably, a linear C₆ alkyl group); wherein b is an average of 0 to 3 (preferably, 0 to 2; more preferably 2); wherein c is an average of 0 to 3 (preferably, 0 to 2; more preferably 0); and with the proviso that b+c is an average of 1 to 3 (preferably, 2 to 3; more preferably, 2). More preferably, the hard surface cleaning concentrate packet of the present invention, comprises: a concentrated hard surface cleaning composition, comprising: 15 to 50 wt % (preferably, 20 to 40 wt %; more preferably, 25 to 30 wt %; most preferably, 26 to 28 wt %), based on weight of the concentrated hard surface cleaning composition, of a glycol ether of formula Ia; wherein R¹ is a linear C₄₋₇ alkyl group; wherein b is 2; and wherein c is 0. Most preferably, the hard surface cleaning concentrate packet of the present invention, comprises: a concentrated hard surface cleaning composition, comprising: 15 to 50 wt % (preferably, 20 to 40 wt %; more preferably, 25 to 30 wt %; most preferably, 26 to 28 wt %), based on weight of the concentrated hard surface cleaning composition, of a glycol ether of formula Ia; wherein R¹ is a linear C₆ alkyl group; wherein b is 2; and wherein c is 0.

Preferably, the hard surface cleaning concentrate packet of the present invention, comprises: a concentrated hard surface cleaning composition, comprising: 20 to 60 wt % (preferably, 25 to 50 wt %; more preferably, 30 to 40 wt %;

most preferably, 34 to 38 wt %), based on weight of the concentrated hard surface cleaning composition, of a non-ionic surfactant of formula II

wherein w is an average of 5 to 40 (preferably, 7 to 27; more preferably, 8 to 20; most preferably, 7 to 12); wherein R³ is selected from the group consisting of a hydrogen and a linear or branched C₁₋₂₀ alkyl group (preferably, a hydrogen, and a linear or branched C₁₋₁₅ alkyl group; more preferably, a linear C₁₋₁₅ alkyl group); wherein R⁴ is selected from the group consisting of a linear or branched C₁₋₂₀ alkyl group and a linear or branched C₁₋₄ hydroxyalkyl group (preferably, a linear or branched C₁₋₁₅ alkyl group and a linear or branched C₁₋₄ hydroxyalkyl group; more preferably, a linear C₁₋₁₅ alkyl group and a linear or branched C₁₋₃ hydroxyalkyl group; most preferably, a linear C₁₋₁₅ alkyl group); wherein each R⁵ is independently selected from the group consisting of a hydrogen, a methyl group, an ethyl group, a n-propyl group, an iso-propyl group, a n-butyl group, a 2-butyl group and a 2-methyl-2-butyl group (preferably, a hydrogen, a methyl group and an ethyl group; more preferably, a hydrogen and a methyl group; most preferably, a hydrogen); and with the proviso that sum of the total number of carbon atoms in R³ and R⁴ is 5 to 21 (preferably, 6 to 20 carbon atoms; more preferably, 7 to 18 carbon atoms; most preferably, 11 to 15 carbon atoms). More preferably, the hard surface cleaning concentrate packet of the present invention, comprises: a concentrated hard surface cleaning composition, comprising: 20 to 60 wt % (preferably, 25 to 50 wt %; more preferably, 30 to 40 wt %; most preferably, 34 to 38 wt %), based on weight of the concentrated hard surface cleaning composition, of a nonionic surfactant of formula II; wherein w is an average of 8 to 16; wherein R³ is selected from the group consisting of a hydrogen and a linear C₁₋₁₅ alkyl group; wherein R⁴ is selected from the group consisting of a linear or branched C₁₋₁₅ alkyl group and a linear or branched C₁₋₄ hydroxyalkyl; and with the proviso that the sum of the total number of carbon atoms in R³ and R⁴ is 6 to 20. Most preferably, the hard surface cleaning concentrate packet of the present invention, comprises: a concentrated hard surface cleaning composition, comprising: 20 to 60 wt % (preferably, 25 to 50 wt %; more preferably, 30 to 40 wt %; most preferably, 34 to 38 wt %), based on weight of the concentrated hard surface cleaning composition, of a non-ionic surfactant of formula II; wherein w is an average of 7 to 12; wherein R³ is selected from the group consisting of a hydrogen and a linear C₁₋₁₅ alkyl group; wherein R⁴ is selected from the group consisting of a linear C₁₋₁₅ alkyl group and a linear or branched C₁₋₃ hydroxyalkyl group; and with the proviso that the sum of the total number of carbon atoms in R³ and R⁴ is 7 to 18.

Preferably, the hard surface cleaning concentrate packet of the present invention, comprises: a concentrated hard surface cleaning composition, comprising: 20 to 60 wt % (preferably, 25 to 50 wt %; more preferably, 30 to 40 wt %; most preferably, 34 to 38 wt %), based on weight of the concentrated hard surface cleaning composition, of a non-ionic surfactant of formula II, wherein the nonionic surfactant of formula II is of formula IIa

wherein x is an average of 5 to 15 (preferably, 7 to 12; more preferably, 8 to 10); wherein y is an average of 0 to 15 (preferably, 0 to 10; more preferably, 0 to 8; most preferably, 0 to 6); wherein R³ is selected from the group consisting of a hydrogen and a linear or branched C₁₋₂₀ alkyl group (preferably, a hydrogen and a linear or branched C₁₋₁₅ alkyl group; more preferably, a linear C₁₋₁₅ alkyl group); wherein R⁴ is selected from the group consisting of a linear or branched C₁₋₂₀ alkyl group and a linear or branched C₁₋₄ hydroxyalkyl group (preferably, a linear or branched C₁₋₁₅ alkyl group and a linear or branched C₁₋₄ hydroxyalkyl group; more preferably, a linear C₁₋₁₅ alkyl group and a linear or branched C₁₋₃ hydroxyalkyl group; most preferably, a linear C₁₋₁₅ alkyl group); and with the proviso that the sum of the total number of carbon atoms in R³ and R⁴ is 5 to 21 (preferably, 6 to 20 carbon atoms; more preferably, 7 to 18 carbon atoms; most preferably, 11 to 15 carbon atoms). More preferably, the hard surface cleaning concentrate packet of the present invention, comprises: a concentrated hard surface cleaning composition, comprising: 20 to 60 wt % (preferably, 25 to 50 wt %; more preferably, 30 to 40 wt %; most preferably, 34 to 38 wt %), based on weight of the concentrated hard surface cleaning composition, of a non-ionic surfactant of formula IIa; wherein x is an average of 8 to 10; wherein y is an average of 0 to 6; wherein R³ is selected from the group consisting of a hydrogen and a linear C₁₋₁₅ alkyl group; wherein R⁴ is selected from the group consisting of a linear or branched C₁₋₁₅ alkyl group and a linear or branched C₁₋₃ hydroxyalkyl group; and with the proviso that the sum of the total number of carbon atoms in R³ and R⁴ is 6 to 20. Most preferably, the hard surface cleaning concentrate packet of the present invention, comprises: a concentrated hard surface cleaning composition, comprising: 20 to 60 wt % (preferably, 25 to 50 wt %; more preferably, 30 to 40 wt %; most preferably, 34 to 38 wt %), based on weight of the concentrated hard surface cleaning composition, of a non-ionic surfactant of formula IIa; wherein x is an average of 7 to 12; wherein y is 0; wherein R³ is a linear C₁₋₁₅ alkyl group; wherein R⁴ is a linear C₁₋₁₅ alkyl group; and with the proviso that the sum of the total number of carbon atoms in R³ and R⁴ is 7 to 18.

Preferably, the hard surface cleaning concentrate packet of the present invention, comprises: a concentrated hard surface cleaning composition, comprising: 15 to 60 wt % (preferably, 20 to 50 wt %; more preferably, 25 to 40 wt %; most preferably, 27 to 34 wt %), based on weight of the concentrated hard surface cleaning composition, of a tertiary amine. More preferably, the hard surface cleaning concentrate packet of the present invention, comprises: a concentrated hard surface cleaning composition, comprising: 15 to 60 wt % (preferably, 20 to 50 wt %; more preferably, 25 to 40 wt %; most preferably, 27 to 34 wt %), based on weight of the concentrated hard surface cleaning composition, of a tertiary amine; wherein the tertiary amine is according to formula III

wherein R⁶, R⁷ and R⁸ are independently selected from a linear or branched C₁₋₂₀ alkyl group (preferably; a linear or branched C₁₋₁₀ alkyl group and a linear or branched C₁₋₁₀ hydroxyalkyl group; more preferably, a branched C₃₋₅ alkyl group and a branched C₃₋₅ hydroxyalkyl group; most preferably, a branched C₃ hydroxyalkyl group). Still more preferably, the hard surface cleaning concentrate packet of the present invention, comprises: a concentrated hard surface cleaning composition, comprising: 15 to 60 wt % (preferably, 20 to 50 wt %; more preferably, 25 to 40 wt %; most preferably, 27 to 34 wt %), based on weight of the concentrated hard surface cleaning composition, of a tertiary amine of formula III; wherein R⁶, R⁷ and R⁸ are independently selected from the group consisting of a linear or branched C₁₋₁₀ alkyl group and a linear or branched C₁₋₁₀ hydroxyalkyl group. Yet more preferably, the hard surface cleaning concentrate packet of the present invention, comprises: a concentrated hard surface cleaning composition, comprising: 15 to 60 wt % (preferably, 20 to 50 wt %; more preferably, 25 to 40 wt %; most preferably, 27 to 34 wt %), based on weight of the concentrated hard surface cleaning composition, of a tertiary amine of formula III; wherein R⁶, R⁷ and R⁸ are independently selected from the group consisting of a branched C₃₋₅ alkyl group and a branched C₃₋₅ hydroxyalkyl group. Most preferably, the hard surface cleaning concentrate packet of the present invention, comprises: a concentrated hard surface cleaning composition, comprising: 15 to 60 wt % (preferably, 20 to 50 wt %; more preferably, 25 to 40 wt %; most preferably, 27 to 34 wt %), based on weight of the concentrated hard surface cleaning composition, of a tertiary amine of formula III; wherein R⁶, R⁷ and R⁸ are a branched C₃ hydroxyalkyl group.

The concentrated hard surface cleaning composition of the present invention, optionally further comprises an optional ingredient. Preferably, the concentrated hard surface cleaning composition of the present invention, further comprises an optional ingredient; wherein the optional ingredient is selected from the group consisting of a salt, an enzyme, a corrosion inhibitor, an acid, a bleaching agent, an abrasive, an antimicrobial agent (e.g., phenoxyethanol, benzalkonium chloride), a rheology modifier, a film former (e.g., Acusol^{TM} Pro), a pH adjuster, a buffering agent, an aesthetic colorant, a fragrance and mixtures thereof.

Preferably, the hard surface cleaning concentrate packet of the present invention, comprises: a concentrated hard surface cleaning composition; wherein the concentrated hard surface cleaning composition includes an aesthetic colorant. More preferably, the hard surface cleaning concentrate packet of the present invention, comprises: a concentrated hard surface cleaning composition; wherein the concentrated hard surface cleaning composition includes 0.05 to 3 wt % (preferably, 0.1 to 2.5 wt %; more preferably, 0.5 to 2.0 wt %; most preferably, 0.5 to 1.5 wt %), based on weight of the concentrated hard surface cleaning composition, of an aesthetic colorant. Still more preferably, the hard surface cleaning concentrate packet of the present invention, comprises: a concentrated hard surface cleaning composition; wherein the concentrated hard surface cleaning composition includes 0.05 to 3 wt % (preferably, 0.1 to 2.5 wt %; more preferably, 0.5 to 2.0 wt %; most preferably, 0.5 to 1.5 wt %), based on weight of the concentrated hard surface cleaning composition, of an aesthetic colorant; wherein the aesthetic colorant is selected from the group consisting of dyes (e.g., small molecule dyes and polymeric dyes), dye-clay conjugates and pigments. Most preferably, the hard surface cleaning concentrate packet of the present invention, comprises: a concentrated hard surface cleaning composi-

tion; wherein the concentrated hard surface cleaning composition includes 0.05 to 3 wt % (preferably, 0.1 to 2.5 wt %; more preferably, 0.5 to 2.0 wt %; most preferably, 0.5 to 1.5 wt %), based on weight of the concentrated hard surface cleaning composition, of an aesthetic colorant; wherein the aesthetic colorant is selected from the group consisting of dyes (e.g., small molecule dyes and polymeric dyes), dye-clay conjugates, pigments and Liquitint® polymeric colorants (available from Milliken & Company); wherein the aesthetic colorant contains at least one chromophore constituent selected from the group consisting of acridines, anthraquinones, azines, azos, benzodifuranes, benzodifuranes, carotenoids, coumarins, cyanines, diazahemicyanines, diphenylmethanes, formazans, hemicyanines, indigoids, methanes, methines, naphthalimides, naphthoquinones, nitros, nitrosos, oxazines, phenothiazine, phthalocyanines, pyrazoles, pyrazolones, quinolones, stilbenes, styryls, triarylmethanes, xanthenes and mixtures thereof. Aesthetic colorants include, for example, polymeric colorants such as Liquitint® Yellow EC, Liquitint® Red OC, Liquitint® Blue AH, Liquitint® Blue BB, Liquitint® Blue 275, Liquitint® Blue 297, Liquitint® Blue BB, Cyan 15, Liquitint® Green 101, Liquitint® Orange 272, Liquitint® Orange 255, Liquitint® Pink AM, Liquitint® Pink AMC, Liquitint® Pink ST, Liquitint® Violet 129, Liquitint® Violet 291, Liquitint® Violet LS, Liquitint® Yellow FT, Liquitint® Blue Buf, Liquitint® Pink AM, Liquitint® Pink PV, Acid Blue 80, Acid Blue 182, Acid Red 33, Acid Red 52, Acid Violet 48, Acid Violet 126, Acid Blue 9, Acid Blue 1 and mixtures thereof (preferably, a mixture of Liquitint® Yellow EC and Liquitint® Red OC).

Preferably, the hard surface cleaning concentrate packet of the present invention, comprises: a concentrated hard surface cleaning composition; wherein the concentrated hard surface cleaning composition includes a fragrance. More preferably, the hard surface cleaning concentrate packet of the present invention, comprises: a concentrated hard surface cleaning composition; wherein the concentrated hard surface cleaning composition includes 0.01 to 5 wt % (preferably, 0.1 to 4.5 wt %; more preferably, 1 to 4.25 wt %; most preferably, 2 to 4 wt %), based on weight of the concentrated hard surface cleaning composition, of a fragrance.

Preferably, the concentrated hard surface cleaning composition has a pH of ≤11. More preferably, the concentrated hard surface cleaning composition has a pH of 5 to 10.5. Most preferably, the concentrated hard surface cleaning composition has a pH of 8 to 10.

Preferably, the concentrated hard surface cleaning composition of the present invention contains 0 to 10 wt % (preferably, 0 to 5 wt %; more preferably, 0 to 2.5 wt %; still more preferably, 0 to 2 wt %; yet more preferably, 0 to 1.5 wt %; most preferably, 0 to 1 wt %) of water.

Preferably, the concentrated hard surface cleaning composition of the present invention contains <0.01 wt % (preferably, <0.001 wt %; more preferably, <0.0001 wt %; still more preferably, <0.0001 wt %; most preferably, less than the detectable limit) of dispersant polymer. More preferably, the concentrated hard surface cleaning composition of the present invention contains <0.01 wt % (preferably, <0.001 wt %; more preferably, <0.0001 wt %; still more preferably, <0.0001 wt %; most preferably, less than the detectable limit) of dispersant polymer; wherein the dispersant polymer is selected from the group consisting of poly(acrylic acid), poly(acrylic acid/maleic acid) copolymers, poly(maleic acid/olefin) copolymers, phosphino carboxylated polymers and mixtures thereof.

11

Preferably, the concentrated hard surface cleaning composition of the present invention contains <5 wt % (preferably, 0 to 3 wt %; more preferably, 0 to 2.6 wt %) of quaternary ammonium compounds (e.g., benzalkonium).

Preferably, the concentrated hard surface cleaning composition of the present invention contains <0.01 wt % (preferably, <0.001 wt %; more preferably, <0.0001 wt %; still more preferably, <0.0001 wt %; most preferably, less than the detectable limit) of hydrotrope. More preferably, the concentrated hard surface cleaning composition of the present invention contains <0.01 wt % (preferably, <0.001 wt %; more preferably, <0.0001 wt %; still more preferably, <0.0001 wt %; most preferably, less than the detectable limit) of hydrotrope; wherein the hydrotrope is selected from the group consisting of calcium, sodium, potassium, ammonium and alkanol ammonium salts of xylene sulfonic acid; calcium, sodium, potassium, ammonium and alkanol ammonium salts of toluene sulfonic acid; calcium, sodium, potassium, ammonium and alkanol ammonium salts of ethylbenzene sulfonic acid; calcium, sodium, potassium, ammonium and alkanol ammonium salts of cumene sulfonic acid; and mixtures thereof.

Preferably, the method of making a hard surface cleaning concentrate packet of the present invention, comprises: providing a water soluble film (preferably, wherein the water soluble film has a disintegration time of less than 90 seconds as determined at 40° C. using distilled water according to MSTM 205 when measured independently from the concentrated hard surface cleaning composition); selecting a glycol ether of formula I

wherein R^1 is a linear or branched C_{2-8} alkyl group (preferably, a linear or branched C_{3-8} alkyl group; more preferably, a linear C_{4-7} alkyl group; most preferably, a linear C_6 alkyl group); wherein each R^2 is independently selected from the group consisting of a hydrogen and a methyl group (preferably, wherein each R^2 is a hydrogen); and wherein a is 1 to 3 (preferably, wherein a is 2); selecting a nonionic surfactant of formula II

(II)

wherein w is an average of 5 to 40 (preferably, 7 to 27; more preferably, 8 to 20; most preferably, 7 to 12); wherein R^3 is selected from the group consisting of a hydrogen and a linear or branched C_{1-20} alkyl group (preferably, a hydrogen, and a linear or branched C_{1-15} alkyl group; more preferably, a linear C_{1-15} alkyl group); wherein R^4 is selected from the group consisting of a linear or branched C_{1-20} alkyl group and a linear or branched C_{1-4} hydroxyalkyl group (preferably, a linear or branched C_{1-15} alkyl group and a linear or branched C_{1-4} hydroxyalkyl group; more preferably, a linear C_{1-15} alkyl group and a linear or branched C_{1-3} hydroxyalkyl group; most preferably, a linear C_{1-15} alkyl group); wherein each R^5 is independently selected from the group consisting of a hydrogen, a methyl group, an ethyl group, a n-propyl group, an iso-propyl group, a n-butyl group, a 2-butyl group and a 2-methyl-2-butyl group (preferably, a hydrogen, a methyl group and an ethyl group; more preferably, a hydrogen and a methyl group; most preferably, a hydrogen); and with the proviso that sum of the total number of carbon

12

atoms in R^3 and R^4 is 5 to 21 (preferably, 6 to 20 carbon atoms; more preferably, 7 to 18 carbon atoms; most preferably, 11 to 15 carbon atoms); and selecting a tertiary amine (preferably, wherein the tertiary amine is of formula III

wherein R^6 , R^7 and R^8 are independently selected from the group consisting of a linear or branched C_{1-20} alkyl group and a C_{1-20} hydroxyalkyl group (preferably, a linear or branched C_{1-10} alkyl group and a linear or branched C_{1-10} hydroxyalkyl group; more preferably, a branched C_{3-5} alkyl group and a C_{3-5} hydroxyalkyl group; most preferably, a branched C_3 hydroxyalkyl group); providing the selected glycol ether of formula I; providing the selected nonionic surfactant of formula II; providing the selected tertiary amine; combining the selected glycol ether of formula I, the selected nonionic surfactant of formula II and the selected tertiary amine to form a concentrated hard surface cleaning composition (preferably, wherein the concentrated hard surface cleaning composition comprises: 15 to 50 wt % (preferably, 20 to 40 wt %; more preferably, 25 to 30 wt %; most preferably, 26 to 28 wt %), based on weight of the concentrated hard surface cleaning composition, of the glycol ether of formula I; 20 to 60 wt % (preferably, 25 to 50 wt %; more preferably, 30 to 40 wt %; most preferably, 34 to 37 wt %), based on weight of the concentrated hard surface cleaning composition, of the nonionic surfactant of formula II; and 20 to 60 wt % (more preferably, 25 to 50 wt %; still more preferably, 30 to 40 wt %; most preferably, 33 to 37 wt %), based on weight of the concentrated hard surface cleaning composition, of the tertiary amine); forming the hard surface cleaning concentrate packet by disposing the concentrated hard surface cleaning composition within an enclosed volume formed by the water soluble film (preferably, wherein the water soluble film is configured into a water soluble film pouch)(the water soluble film pouch may have one or multiple cavities for receiving the concentrated hard surface cleaning composition, or portion thereof)(preferably, the water soluble film pouch has one cavity for receiving the concentrated hard surface cleaning composition), wherein the water soluble film encapsulates the concentrated hard surface cleaning composition.

Preferably, the method of making a hard surface cleaning concentrate packet of the present invention, comprises: providing a water soluble film (preferably, wherein the water soluble film has a disintegration time of less than 90 seconds as determined at 40° C. using distilled water according to MSTM 205 when measured independently from the concentrated hard surface cleaning composition); selecting a glycol ether of formula I, wherein the glycol ether of formula I is of formula Ia

wherein R^1 is a linear or branched C_{2-8} alkyl group (preferably, a linear or branched C_{3-8} alkyl group; more preferably, a linear C_{4-7} alkyl group; most preferably, a linear C_6

13

alkyl group); wherein b is an average of 0 to 3 (preferably, 0 to 2; more preferably 2); wherein c is an average of 0 to 3 (preferably, 0 to 2; more preferably 0); and with the proviso that b+c is an average of 1 to 3 (preferably, 2 to 3; more preferably, 2); selecting a nonionic surfactant of formula II, wherein the nonionic surfactant of formula II is of formula IIa

(IIa)

10

wherein x is an average of 5 to 15 (preferably, 7 to 12; more preferably, 8 to 10); wherein y is an average of 0 to 15 (preferably, 0 to 10; more preferably, 0 to 8; most preferably, 0 to 6); wherein R³ is selected from the group consisting of a hydrogen and a linear or branched C₁₋₂₀ alkyl group (preferably, a hydrogen and a linear or branched C₁₋₁₅ alkyl group; more preferably, a linear C₁₋₁₅ alkyl group); wherein R⁴ is selected from the group consisting of a linear or branched C₁₋₂₀ alkyl group and a linear or branched C₁₋₄ hydroxyalkyl group (preferably, a linear or branched C₁₋₁₅ alkyl group and a linear or branched C₁₋₄ hydroxyalkyl group; more preferably, a linear C₁₋₁₅ alkyl group and a linear or branched C₁₋₃ hydroxyalkyl group; most preferably, a linear C₁₋₁₅ alkyl group); and with the proviso that the sum of the total number of carbon atoms in R³ and R⁴ is 5 to 21 (preferably, 6 to 20 carbon atoms; more preferably, 7 to 18 carbon atoms; most preferably, 11 to 15 carbon atoms); and selecting a tertiary amine (preferably, wherein the tertiary amine is of formula III

wherein R⁶, R⁷ and R⁸ are independently selected from the group consisting of a linear or branched C₁₋₂₀ alkyl group and a linear or branched C₁₋₂₀ hydroxyalkyl group (preferably; a linear or branched C₁₋₁₀ alkyl group and a linear or branched C₁₋₁₀ hydroxyalkyl group; more preferably, a branched C₃₋₅ alkyl group and a branched C₃₋₅ hydroxyalkyl group; most preferably, a branched C₃ hydroxyalkyl group); providing the selected glycol ether of formula Ia; providing the selected nonionic surfactant of formula IIa; providing the selected tertiary amine; combining the selected glycol ether of formula Ia, the selected nonionic surfactant of formula IIa and the selected tertiary amine to form a concentrated hard surface cleaning composition (preferably, wherein the concentrated hard surface cleaning composition comprises: 15 to 50 wt % (preferably, 20 to 40 wt %; more preferably, 25 to 30 wt %; most preferably, 26 to 28 wt %), based on weight of the concentrated hard surface cleaning composition, of the glycol ether of formula Ia; 20 to 60 wt % (preferably, 25 to 50 wt %; more preferably, 30 to 40 wt %; most preferably, 34 to 38 wt %), based on weight of the concentrated hard surface cleaning composition, of the nonionic surfactant of formula IIa; and 15 to 60 wt % (more preferably, 20 to 50 wt %; still more preferably, 25 to 40 wt %; most preferably, 27 to 34 wt %), based on weight of the concentrated hard surface cleaning composition, of the tertiary amine); forming the hard surface cleaning concentrate packet by dispos-

14

ing the concentrated hard surface cleaning composition within an enclosed volume formed by the water soluble film (preferably, wherein the water soluble film is configured into a water soluble film pouch)(the water soluble film pouch may have one or multiple cavities for receiving the concentrated hard surface cleaning composition, or portion thereof) (preferably, the water soluble film pouch has one cavity for receiving the concentrated hard surface cleaning composition), wherein the water soluble film encapsulates the concentrated hard surface cleaning composition.

Preferably, the water soluble film pouch used in the hard surface cleaning concentrate packet of the present invention forms a sealed container containing the concentrated hard surface cleaning composition. The sealed container can be formed from the water soluble film by any suitable method, including thermoforming, heat sealing, solvent welding and use of adhesive sealing solutions (e.g., with use of a water-soluble adhesive).

This disclosure also provides a method of forming the encapsulated cleaning composition. The method includes the step of providing a water soluble film, providing a concentrated hard surface cleaning composition and disposing (e.g., pouring, inserting, injecting or otherwise placing) the concentrated cleaning composition within a containment volume (or containment volumes) formed using the water soluble film.

Preferably, the water soluble film pouch used in the hard surface cleaning concentrate packet of the present invention is stable in the presence of the concentrated hard surface cleaning composition. In use, the hard surface cleaning concentrate packet of the present invention is combined with a dilution water. Following combination with the dilution water, the water soluble film readily disintegrates, releasing the concentrated hard surface cleaning composition into the dilution water to form a hard surface cleaning use composition. Preferably, the volume ratio between the concentrated hard surface cleaning composition and the dilution water of 1:1,000 (preferably, 1:5 to 1:500; more preferably, 1:7.5 to 1:250; still more preferably, 1:10 to 1:150; most preferably, 1:15 to 1:50).

Preferably, the method of removing oily, greasy, tough and stubborn soils from a hard surface of the present invention, comprises: providing a soiled hard surface (preferably, wherein the soiled hard surface is selected from the group consisting of a counter top surface, a cook top surface, a ceramic surface, a laminate surface, a porcelain surface, a tile surface, a glass surface, a metal surface, a wood surface; preferably, the soiled hard surface is a nonporous surface) (preferably, the soiled hard surface is soiled with at least one of an oily soil or a greasy soil); providing a container (preferably, a volume specific container designed for the surface cleaning task); providing a dilution water (preferably, distilled water); selecting a hard surface cleaning concentrate packet prepared according to the method of the present invention; providing the selected hard surface cleaning concentrate packet; combining (optionally, combining with at least one of agitation and heat) the selected hard surface cleaning concentrate packet and the dilution water in the container (preferably, wherein the container is a volume specific spray bottle designed to receive a measured volume of dilution water and the hard surface cleaning concentrate packet) to form a hard surface cleaning use composition; wetting the soiled hard surface with the hard surface cleaning use composition; and wiping (optionally, rubbing; optionally, scrubbing) the wetted soiled hard surface (preferably with an implement selected from the group consisting

of a cloth, towel, wipe, brush, mop, wiper, squeegee, sponge or a combination thereof) to provide a cleaned hard surface.

Some embodiments of the present invention will now be described in detail in the following Examples.

Comparative Examples C1-C10 and Examples 1-2

Concentrated Hard Surface Cleaning Composition

Concentrated hard surface cleaning compositions of Comparative Examples C₁-C₁₀ and Examples 1-2 were prepared by mixing together the components in the weight proportions noted in TABLE 1.

Soil Removal Tests

The soil removal performance of concentrated hard surface cleaning compositions of Comparative Examples C2, C5, C7 and C8 and Example 1 were diluted at a 1:20 volume dilution ratio with deionized water to form the test solutions. According to IKW recommendations, 1,500 μ L fat dust soil/tiles were placed in an oven set at 120° C. for 24 hours. The tiles were then removed from the oven and were kept in a climate controlled laboratory for 24 hours at room temperature before testing. The fat dust soil used was comprised of 75 wt % peanut oil, 23 wt % kaolin and 2 wt % carbon black dispersed in isopropyl alcohol (20 wt % soil/80 wt % isopropyl alcohol). A scrub machine was used to perform the tests. For each test, a 3 mL portion of the test solution was placed on a sponge (soft side) and then the soiled tile was stroked 10 times with the test solution wetted surface of the sponge. The tiles were then rinsed under running tap water before evaluating the test results. The cleaning formulation of Comparative Example C2 showed the best performance followed by Comparative Example C5, Comparative Example C8, Comparative Example C7 and then Example 1. Note, however, that the formulation of Comparative Example C2 gave off an ammonia odor upon dilution; the formulations of Comparative Examples C5 and C7 required heat to disperse the amine used therein; and the formulation of Comparative Example C8 required heat to disperse the amine, which precipitated back out of solution upon cooling to room temperature.

Soil Removal Tests

The soil removal performance of concentrated hard surface cleaning compositions of Comparative Example C9 and Example 2 were diluted at a 1:20 volume dilution ratio with deionized water to form the test solutions. According to IKW recommendations, 1,500 μ L fat dust soil/tiles were placed in an oven set at 120° C. for 24 hours. The tiles were then removed from the oven and were kept in a climate controlled laboratory for 24 hours at room temperature before testing. The fat dust soil used was comprised of 75 wt % peanut oil, 23 wt % kaolin and 2 wt % carbon black dispersed in isopropyl alcohol (20 wt % soil/80 wt % isopropyl alcohol). A scrub machine was used to perform the tests. For each test, a 3 mL portion of the test solution was placed on a sponge (soft side) and then the soiled tile was stroked 10 times with the test solution wetted surface of the sponge. The tiles were then rinsed under running tap water before evaluating the test results. The cleaning formulation of Example 2 showed drastically better performance compared to that of Comparative Example C9, demonstrating the dramatic impact of solvent choice on cleaning formulation performance.

Example 3

Concentrated Hard Surface Cleaning Composition

Concentrated hard surface cleaning composition of Example 3 was prepared by mixing together the components in the weight proportions noted in TABLE 2.

TABLE 2

⁴Liquitint Yellow EC available from Milliken Chemical

⁵Liquitint Red OC available from Milliken Chemical

Soil Removal Tests

The soil removal performance of the concentrated hard surface cleaning composition of Example 3 diluted at a 1:20 volume dilution ratio with deionized water to form the test solutions. The cleaning performance of the cleaning solution of Example 3 was compared with that of three commercial products—Mr Proper, St Marc and Ajax. According to IKW recommendations, 1,500 μ L fat dust soil/tiles were placed in an oven set at 120° C. for 24 hours. The tiles were then removed from the oven and were kept in a climate controlled laboratory for 24 hours at room temperature before testing. The fat dust soil used was comprised of 75 wt % peanut oil, 23 wt % kaolin and 2 wt % carbon black dispersed in isopropyl alcohol (20 wt % soil/80 wt % isopropyl alcohol). A scrub machine was used to perform the tests. For each test, a 3 mL portion of the test solution was placed on a sponge (soft side) and then the soiled tile was stroked 10 times with the test solution wetted surface of the sponge. The tiles were then rinsed under running tap water before evaluating the

test results. The cleaning formulation of Example 3 significantly outperformed each of the commercial formulations on the tested fat dust soil.

We claim:

1. A hard surface cleaning concentrate packet, comprising:
  - a water soluble film;
  - a concentrated hard surface cleaning composition, comprising:
    - 15 to 50 wt %, based on weight of the concentrated hard surface cleaning composition, of a glycol ether of formula I

wherein R^1 is a linear or branched C_{2-8} alkyl group; wherein each R^2 is independently selected from the group consisting of a hydrogen and a methyl group; and wherein a is 1 to 3;

20 20 to 60 wt %, based on weight of the concentrated hard surface cleaning composition, of a nonionic surfactant of formula II

wherein w is an average of 5 to 40; wherein R^3 is selected from the group consisting of a hydrogen and a linear or branched C_{1-20} alkyl group; wherein R^4 is selected from the group consisting of a linear or branched C_{1-20} alkyl group and a linear or branched C_{1-4} hydroxyalkyl group; wherein each R^5 is independently selected from the group consisting of a hydrogen, a methyl group, an ethyl group, a n-propyl group, an iso-propyl group, a n-butyl group, a 2-butyl group and a 2-methyl-2-butyl group; and with the proviso that sum of the total number of carbon atoms in R^3 and R^4 is 5 to 21; and 35 15 to 60 wt %, based on weight of the concentrated hard surface cleaning composition, of a tertiary amine; wherein the water soluble film encapsulates the concentrated hard surface cleaning composition.

2. The hard surface cleaning concentrate packet of claim 1, wherein the tertiary amine is of formula III

wherein R^6 , R^7 and R^8 are independently selected from the group consisting of a linear or branched C_{1-20} alkyl group and a linear or branched C_{1-20} hydroxyalkyl group.

3. The hard surface cleaning concentrate packet of claim 2, wherein R^1 is a linear C_{4-7} alkyl group; wherein a is 2.

4. The hard surface cleaning concentrate packet of claim 3, wherein w is an average of 8 to 16; wherein R^3 is a linear C_{1-15} alkyl group; wherein R^4 is a linear C_{1-15} alkyl group; with the proviso that the sum of the total number of carbon atoms in R^3 and R^4 is 6 to 20.

5. The hard surface cleaning concentrate packet of claim 4, wherein R^6 , R^7 and R^8 are independently selected from

the group consisting of a linear or branched C_{1-10} alkyl group and a linear or branched C_{1-10} hydroxyalkyl group.

6. The hard surface cleaning concentrate packet of claim 5, wherein R^6 , R^7 and R^8 are independently selected from the group consisting of a linear or branched C_{1-10} hydroxyalkyl group.

7. The hard surface cleaning concentrate packet of claim 5, wherein R^6 , R^7 and R^8 are independently selected from the group consisting of a branched C_{3-5} alkyl group and a branched C_{3-5} hydroxyalkyl group.

8. The hard surface cleaning concentrate packet of claim 7, wherein R^6 , R^7 and R^8 are a branched C_3 hydroxyalkyl group.

9. A method of making a hard surface cleaning concentrate packet, comprising:
  - providing a water soluble film;
  - selecting a glycol ether of formula I

wherein R^1 is a linear or branched C_{2-8} alkyl group; wherein each R^2 is independently selected from the group consisting of a hydrogen and a methyl group; and wherein a is 1 to 3;

25 30 selecting a nonionic surfactant of formula II

wherein w is an average of 5 to 40; wherein R^3 is selected from the group consisting of a hydrogen and a linear or branched C_{1-20} alkyl group; wherein R^4 is selected from the group consisting of a linear or branched C_{1-20} alkyl group and a linear or branched C_{1-4} hydroxyalkyl group; wherein each R^5 is independently selected from the group consisting of a hydrogen, a methyl group, an ethyl group, a n-propyl group, an iso-propyl group, a n-butyl group, a 2-butyl group and a 2-methyl-2-butyl group; and with the proviso that sum of the total number of carbon atoms in R^3 and R^4 is 5 to 21; and 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 combining the selected hard surface cleaning concentrate packet and the dilution water in the container to form a hard surface cleaning use composition; wetting the soiled hard surface with the hard surface cleaning use composition; and wiping the wetted soiled hard surface to provide a cleaned hard surface.

11. The hard surface cleaning concentrate packet of claim **8**, wherein the concentrated hard surface cleaning composition, comprises:

20 to 40 wt %, based on weight of the concentrated hard surface cleaning composition, of the glycol ether of formula I;

25 to 50 wt %, based on weight of the concentrated hard surface cleaning composition, of the nonionic surfactant of formula II; and

20 to 50 wt %, based on weight of the concentrated hard surface cleaning composition, of the tertiary amine.

12. The hard surface cleaning concentrate packet of claim **8**, wherein the concentrated hard surface cleaning composition, comprises:

5

10

25 to 30 wt %, based on weight of the concentrated hard surface cleaning composition, of the glycol ether of formula I;

30 to 40 wt %, based on weight of the concentrated hard surface cleaning composition, of the nonionic surfactant of formula II; and

25 to 40 wt %, based on weight of the concentrated hard surface cleaning composition, of the tertiary amine.

13. The hard surface cleaning concentrate packet of claim **8**, wherein the concentrated hard surface cleaning composition, comprises:

26 to 28 wt %, based on weight of the concentrated hard surface cleaning composition, of the glycol ether of formula I;

34 to 38 wt %, based on weight of the concentrated hard surface cleaning composition, of the nonionic surfactant of formula II; and

27 to 34 wt %, based on weight of the concentrated hard surface cleaning composition, of the tertiary amine.
